[57] CLAIM

The ornamental design for a scoop for collecting dog waste, as shown and described.

DESCRIPTION

FIG. 1 is a perspective view of a scoop for collecting dog waste showing our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing in the drawings represent perforations and creases.
